CONTAINER PERFORATOR

Lacey E. Fuller, Coeburn, Va.

Application March 3, 1950, Serial No. 147,457

2 Claims. (Cl. 30—16)

1

This invention pertains to kitchen utensils, and more particularly to the class known as can openers and can punches employed to release liquid contents so that they may be poured therefrom.

While various types of devices have been developed and commercially distributed for the opening of canned containers so that the liquid contents may be dispensed, they usually have the disadvantage of not being convenient and effective enough to meet the specific requirements involved. Where the contents to be dispensed are of the milk or cream nature, the desirability of having a device that will provide for an ample opening of the container at the pouring location is appreciable, especially where the liability to drip can be avoided. This invention provides for this feature as well as others. It employs a can perforator that is made with a bracket adapted for mounting on a conventional container, and has a punch situated on it enabling it to punch an orifice therein convenient for the purpose of dispensing the contents without undesirable dripping. It includes a handle for manipulating the punch above the container conveniently, and has guides that definitely control the positioning of its working components and the accuracy of operation.

It is, therefore, an object of this invention to provide a new and improved container perforator that will avoid one or more of the disadvantages and limitations of the prior art.

Another object of the invention is to provide a new and improved container perforator that can be mounted on a conventional can in a safe and convenient manner and will provide a pouring aperture for the discharge of its contents that will be located where it will not induce undesirable dripping.

A further object of the herein-described invention is to provide a new and improved container perforator that can do effective work, present an attractive appearance, can be manufactured economically and will perform its duties without danger to the operator or damage to the contents.

Other objects will become apparent as the invention is more fully outlined. For a more comprehensive understanding of its objects, principles and operation, reference is made to the accompanying drawings, wherein a particular form of the invention is shown. These drawings in conjunction with the following explanation detail the structure and explain its purposes, while the claims indicate the scope thereof.

2

Referring to the drawings, in which like parts are designated by like reference characters throughout the figures:

Figure 1 is a front elevation of a container perforator embodying this invention;

Figure 2 is a sectional elevation on line 2—2 of Figure 1;

Figure 3 is a plan view, partly in section, on line 3—3 of Figure 1; and

10 Figure 4 is a detail in perspective of the cutter head used in this embodiment.

The construction shown in the drawings includes a bracket plate 10, a plunger rod 11 and a coil spring 12, and a handle 13. These components are separable from each other and are adapted for the particular purposes required in their functional operations. The bracket plate 10 is preferably sheet material that is comparatively light and strong so that 15 it will serve to support the other components and bear the stresses involved in using the device for punching holes in a container, by the application of considerable manual force. The bracket plate 10 is bent arcuately to conform with the periphery of a conventional can 15, and has on its upper end a flange 14 bent inwardly therefrom at approximately right angles thereto. The flange 14 has a square hole 16 through which the square cross-section plunger

20 rod 11 reciprocates in a direction parallel to the plane of the bracket plate. A tongue 18 of reduced width depends from the lower end of and is curved like the bracket plate 10. Feet 19 integral with the lower end of the bracket plate 10 25 extend inwardly parallel to the flange 14 at the opposite sides of the tongue 18. These feet 19 serve as rests when the device is placed on a can for perforating it, while the tongue 18 extends downwardly along and against the side of

30 the can and is pressed against the peripheral surface. A pair of guide lugs 20 and 21 are formed in the bracket plate 10 by cutting openings 22, 23, respectively, therein and bending the material therefrom into parallelism with the flange 14 and feet 19. The lugs 20 and 21 have 35 square holes 24 and 25, respectively, of the same size as and aligned with the hole 16 in the flange 14. The plunger rod 11 reciprocates through all of the guide holes 16, 24 and 25. The flange 14 and the upper lug 20 serve as abutments between which the coil spring 12 operates. The spring is loosely circumposed on the rod 11 and a disc 26 is fixed on the rod and engaged with the upper end of the spring so that the spring 40

45 is compressed when the rod is pressed down-

50

55

wardly and acts to raise the rod when downward pressure on the rod is released. The plunger rod 11 projects above the flange 14 where it is provided with a circular handle 13.

The lower portion of the plunger rod extends below the lower lug 21 and has a cutter 30 removably secured thereto so that it can be replaced at any time. The cutter is of the form shown in Figure 4 and has two right triangular walls 27 connected together at their altitude sides, so as to present two downwardly tapered hypotenuse cutting edges. A square recess 31 in its middle portion 28 is designed to receive the lower end of the plunger rod which is held in the recess by a removable pin 29 traversing the sides 27 and portion 28.

The operation of the device is as follows: The bracket 10 is placed on a can of milk 15, or the like, so that the tongue 18 is against the exterior surface of the can and the clips 19 rest on its top. Then the user presses down on the handle 13, overcomes the tension of the spring 12, and forces the plunger 11 downwardly, guided by the rectangular holes 16, 24 and 25, respectively, in the shelf 14 and plates 21. It carries the cutter head 30 down with it and forces the latter into the can top. By reason of the form indicated, it makes a triangular hole in the top, with the apex towards the periphery of the can. Pointed this way, the aperture formed in the can enables the contents to be poured out in a sharply cut stream. The plunger 11 and cutter head 30 are positioned far enough in from the bracket and the periphery of the can as to keep this stream away from the wall edge of the can, and thus does not cause spilling or dripping down the outside of the container. After the aperture is punched, the operator releases his hand from the handle 13 and allows the plunger 11 and cutter head 30 to lift away from the can. The cutter head 30 is normally placed some distance above the can, as shown in the drawings. Then the device is removed from the can and the contents of the latter poured out through the triangular aperture in it.

The construction of the device is relatively simple. The bracket 10 includes the shelf 14, clips 19 and plates 20, all formed from a single blank of material. The bending of the back, shelf, clips and plates strengthens the bracket, even though of thin material. The plunger is guided in three guide holes so that its movement and perforating action is accurate and unwavering. The operation is simple, and the user is protected by the bracket against slippage and injury from the cutter head. Further, the article is compact.

While but one form of the invention is illustrated in this application, it is not desired to limit it to such form, as it is appreciated that other

structures could be developed and made that would employ the same principles and come within the scope of the appended claims.

Having thus described the invention, what is claimed is:

1. In a can punch, a single vertical bracket plate having a tongue depending therefrom for engagement with the side of a can, feet on the lower end of the bracket plate arranged to rest upon the top of the can with said tongue engaged with the side of the can whereby said bracket plate is mounted in operative position on the can, and vertical reciprocable punch means mounted on said bracket plate for punching a hole in the top of the can said punch means comprising a flange on the upper end of the bracket plate, a lug on the bracket plate below and in alignment with said flange, a vertical plunger rod extending through said flange and lug, a can top cutter on the lower end of said rod and below said lug, a handle on the upper end of said rod above said flange, and a coiled spring circumscribed about the rod intermediate the flange and lug and operatively connected to the rod and lug for elevating the plunger rod following compression thereof by manual depression of the plunger rod and release of the plunger rod.
2. In a can punch, a single vertical bracket plate having a tongue depending therefrom for engagement with the side of a can, feet on the lower end of the bracket plate arranged to rest upon the top of the can with said tongue engaged with the side of the can whereby said bracket plate is mounted in operative position on the can, and vertical reciprocable punch means mounted on said bracket plate for punching a hole in the top of the can, said punch means comprising a flange on the upper end of the bracket plate formed with a hole, vertically spaced lugs on the bracket plate below said flange formed with holes aligned with the first-mentioned hole, a vertical plunger rod guidingly extending through all of said holes, said rod having a can top cutter on its lower end below the lowermost lug and a handle on its upper end above said flange.
